UNITED STATES PATENT OFFICE.

JACOB L. WORTMAN, OF WASHINGTON, DISTRICT OF COLUMBIA.

BOOK FOR STYLOGRAPHIC MANIFOLDING.

SPECIFICATION forming part of Letters Patent No. 434,370, dated August 12, 1890.

Application filed March 3, 1890. Serial No. 342,379. (No model.)

To all whom it may concern:

Be it known that I, JACOB L. WORTMAN, a citizen of the United States, residing at Washington, in the District of Columbia, have invented a new and useful Book for Stylographic Manifolding; and I hereby declare the following to be a full, clear, and exact description thereof.

The drawing represents a perspective view 10 of a book made in accordance with my invention.

My invention relates to an improvement in books of the character employed for producing at the same moment a written letter or 15 other document and a counterpart thereof on a separate sheet, the first or so-called "original" being afterward removed from the book, while the duplicate or so-called "copy" remains bound in the book, or vice versa. Books of this nature present two essential 20 characteristics, the first of which is that the operation of making the copy is simultaneous with that of making the original, and the second is that the copy or original thus made is 25 preserved in a permanently-bound condition, like the copies in the ordinary letter-press copy-book.

The features above named have long been 30 recognized as highly desirable, and various ways have been suggested for their attainment. Among these may be mentioned the use of an interposed sheet of ordinary carbon manifolding paper, the face of which is presented to the under sheet, (intended as the 35 original,) while the operation of writing is performed with a graphite pencil upon the upper sheet, (intended as the copy.) Another construction involves the use of exceedingly-thin paper for the copy, and has interposed 40 between this copy-sheet and the sheet intended to receive the original a sheet of carbon manifolding paper having the carbon on both sides. The writing in this is performed on the copy-sheet, as before, but with a stylus, 45 a pencil being unnecessary. The objection to both of these constructions is that the original letter is necessarily written with an easily-eradicated substance, while the copy, being in the first case written on the upper 50 side of the sheet with a lead-pencil and in the second case on the reverse side of the sheet

with easily-removed carbon, fails to present that permanency which is essential to the successful employment of the book in cases where its use as a record is contemplated. A 55 further objection to the second form, in which double-faced carbon-paper is employed with the stylus, is that the legibility of the copy depends upon the degree of translucency of the paper, and this translucency decreases 60 with the thickness and hence with the strength of the paper.

The object of my invention is to produce a book in which stylographic manifolding of the class described may be performed, by the 65 use of which a permanent ineradicable record may be made in the form of an exact counterpart of the original at the same operation by which the original is produced. In other words, the object of my invention is a 70 book by the employment of which a removable letter or other written document, written with a stylus, and a permanent ineradicable counterpart thereof may be prepared at one operation, the counterpart remaining bound 75 in the book and presenting a secure, accurate, and unimpeachable record of the original.

To this end my invention consists in a manifolding-book made up of leaves of paper or other suitable material bound together, 80 preferably having each alternate sheet or one sheet in every three or four, or in less proportion, perforated near its inner edge for easy removal, and preferably having such removable sheet of greater thickness and strength 85 than the others, to render it more suitable for use as a letter-sheet, the book being further provided with a sheet of double-faced manifolding-paper carrying a coloring substance and a permeant vehicle therefor interposed 90 between alternate leaves and capable of being removed or shifted from between one pair of leaves to another pair. The manifolding-paper which I employ differs essentially from the so-called "carbon-paper," and is in a measure 95 an improvement upon the product patented to me January 24, 1888, No. 376,764. As in that patent, the salient characteristic of the manifolding-paper is that it carries the coloring material with a non-drying oil or 100 equivalent permeant vehicle for the color, whereby a quantity of color is conveyed into

and permeates the fiber of the sheet on pressure applied to the reverse side of the manifolding-sheet; but whereas the specific product set forth in that patent, being intended for use in type-writing and similar operations, was necessarily and especially made so that the color while on one side of the manifolding-sheet would be kept from transferring from the other side the product which I employ in combination with the other elements forming my present invention is especially made with a view to giving from both surfaces of the sheet a transfer in equal quantity of the coloring material and its introduction into the fiber of both the upper and lower transfer-sheets by the permeating operation of the non-drying oil or other vehicle; hence in the present specification and claims the product now employed may be designated as a sheet of paper having on both surfaces a color, together with a non-drying oil—such as refined cotton-seed oil—the paper being coated and prepared in a peculiar manner, so as to present a surface of a tinctorial character, yet requiring a slight pressure to cause the transfer of the color to another surface. Such pressure, however, causes the non-drying oil to be transferred to the contiguous transfer-sheet, entering or permeating the fiber thereof and carrying with it a portion of the color in exact representation of the impact or impression by which the transfer was caused. The oil thus acts as a permeant vehicle for the color.

The use of a book of the kind described, having a manifolding-sheet of this description employed in the manner above set forth, preferably with a stylus as the medium of writing, produces as the original a writing made to all intents and purposes with a permeating ink and a copy in which the same character of permeating ink enters the fiber of the copy-paper on the reverse side and appears at the upper surface. The copy-paper is ordinarily of a more bibulous character, as well as thinner, than that for the original; but this is not essential to the use of the book, although the less thin and bibulous the copy-

paper is the less distinct is the copy, owing to the impediment to complete permeation. 50

As the permeability of the tinctorial substance is entirely independent of the condition of the copy-paper, except as described above, it is obvious that either soluble or insoluble colors, or both, may be employed; but I prefer and generally use the insoluble colors, which will not fade when subjected even to the most unfavorable conditions, such as long exposure to sunlight; hence the copy produced possesses not merely the qualities found in the letter-press (wet process) copy, but a durability equal to that of original manuscript written with insoluble ink.

I do not herein claim a manifolding-sheet which carries on both surfaces a coloring substance and a permeant vehicle for the color; neither do I desire herein broadly to claim the specific improvement in the product patented to me January 24, 1888, distinguished as the book made up of alternate leaves of writing and copying paper, unless the same is adapted in the manner and with the additional features described to the production simultaneously of a tinctorial original and copy both of a substantially-permanent character; but

What I claim, and desire to secure by Letters Patent, is—

1. A book for stylographic manifolding, comprising leaves of paper or the like, and having interposed between alternate leaves a removable sheet having on both surfaces a coloring substance, together with a permeant vehicle for the color, substantially as described. 85

2. A book for stylographic manifolding, comprising leaves of alternate writing and copying paper, the writing-paper being provided with perforations for easy removal, and a removable sheet having on both surfaces a coloring substance and a permeant vehicle for the color, substantially as described. 90

JACOB L. WORTMAN.
